UNITED STATES PATENT OFFICE.

EPPA H. RYON, OF WORCESTER, MASSACHUSETTS, ASSIGNOR TO CROMPTON & KNOWLES
LOOM WORKS, A CORPORATION OF MASSACHUSETTS.

WEFT-REPLENISHING LOOM.

939,326.

Specification of Letters Patent.

Patented Nov. 9, 1909.

Application filed July 11, 1908. Serial No. 443,087.

To all whom it may concern:

Be it known that I, EPPA H. RYON, a citizen of the United States, residing at Worcester, in the county of Worcester and State 5 of Massachusetts, have invented certain new and useful Improvements in Weft-Replenishing Looms, of which the following is a specification.

My invention relates to weft replenishing looms, and particularly to that class of weft replenishing looms which have shifting or change shuttle boxes at one end of the loom, and a magazine for bobbins or filling carriers, of different colors or characters, at 15 the other end of the loom, which bobbins or filling carriers are automatically supplied to the active shuttle on the substantial or practical exhaustion of filling in said shuttle.

The object of my invention is to improve 20 upon the construction of the magazine in the class of looms referred to, and of the mechanism connected with the magazine.

My invention consists in certain novel features of construction of my improvements as 25 will be hereinafter fully described.

I have shown in the drawings and will 30 herein describe, a magazine for the bobbins or filling carriers of a rotary type, with my improvements combined therewith. The bobbins or filling carriers are arranged in groups, the different groups containing filling carriers of different colors or characters which correspond with the colors or characters of the filling on the bobbins in the series of shuttles used on the loom. Four or 35 more shuttles may be used as desired. The magazine is moved positively, and in unison with the shifting or change shuttle boxes at the opposite end of the loom, at each change 40 of position of said shuttle boxes, preparatory to supplying the active shuttle with a fresh bobbin or filling carrier, on the substantial or practical exhaustion of the filling therein.

After a bobbin or filling carrier has been re- 45 moved from one group in the magazine, the magazine is moved to carry a new group of bobbins or filling carriers into operative position.

I have shown in the drawings detached 50 parts of a weft replenishing loom of the class referred to, and a rotary magazine, and my improvements combined therewith, sufficient to enable those skilled in the art to understand the construction and operation 55 thereof.

Referring to the drawings:—Figure 1 is a side view of the magazine end of a weft replenishing loom with my improvements combined therewith; the magazine is partially broken away, and the lay is shown in section. Fig. 2 shows, on an enlarged scale, the magazine, and other parts connected therewith, shown in the upper part of Fig. 1; Fig. 3 is a central vertical section through the magazine, on line 3, 3, Fig. 2, looking in the direction of arrow *a*, same figure. Fig. 4 shows, on an enlarged scale, the parts shown in the lower portion of Fig. 1. Fig. 5 is a vertical cross section, on line 5, 5, Fig. 4, looking in the direction of arrow *b*, same figure.

In the accompanying drawings, 1 is the loom side or end frame, 2 is the lay, carried on the lay sword 3 which is pivotally mounted at its lower end at 4, and operated through the crank connector 5 to a crank shaft 6; 7 is a single stationary shuttle box at the magazine end of the loom, with a shuttle 8 therein, carrying a filling carrier or bobbin 9. 10 is the bottom shaft.

Extending up from the loom side 1 and rigidly secured thereto, is a stand 11 having an upper cylindrical portion 11', see Fig. 3. The upper cylindrical shaped portion 11' surrounds the head part of the magazine, and has an opening 11'' therethrough at the lower part thereof, see Fig. 2, through which the head of the bobbin passes when a bobbin is discharged from the magazine. At the central portion of the end 11' is a hub 11''', through which extends the reduced end 12' of a stud 12. The stud 12 is firmly secured in the hub portion 11''' by a nut 13 on the outer threaded end of said stud, and the inner threaded end of the stud 12 has a washer 14 thereon, and a nut 15.

Loosely mounted on the stud 12 is the hollow hub 16 of the magazine. From the hub 16 extends a series of arms or spokes 16', carrying the outer ring 16'' for the tips of the bobbins 9. The ring 16'' has a series of radial notches 16''', in each of which is located a small spring blade 17, see Fig. 3, having its inner bent end at the outer end of the notch, and secured at its inner end by a screw 17'. The spring 17 acts to yieldingly hold the tip of the bobbin within the notches 16''' in the ring 16'' of the magazine. The head of each bobbin 9 is inserted in a pocket or recess 19' in a ring 19. The

ring 19 is connected with and carried by rods 20, which extend transversely between the ring 19 and the ring 16". The rods 20 divide the magazine into compartments, in 5 this instance eight in number, for the groups of bobbins or filling carriers 9, in this instance there are four bobbins in each group.

The reduced ends 20' of the rods 20 extend 10 through the ring 16", and extend inwardly from said ring, and have secured on their ends a ring 21, preferably made out of sheet metal, which forms a surface over which the filling 9' from the bobbins 9 passes, see Fig. 3. The thread ring 21 has 15 notches 21' on its periphery, see Fig. 2, in which notches the filling thread 9' from the bobbins 9 passes, and is wound around and held, preferably by a clamping device consisting of a pin 22 extending loosely through 20 the ring 21, and having a washer or enlarged end 22' on its outer end. A helically coiled expansion spring 23 encircles said pin 22, and bears at one end against a washer 22" on said pin, and at its other end against 25 the threaded ring 21, and acts to yieldingly move outward said pin and the end 22' thereon, to yieldingly hold the end of the filling thread between the end of said pin, and the ring 21. The head 22' is preferably 30 slotted at 22'', see Fig. 2, so that the ends of the threads wound around the pin 22, may be easily cut and removed, if desired.

The outer reduced end 16^a of the hollow hub 16 of the magazine, has loosely mounted 35 thereon the hub 24' of the worm gear 24, which gear meshes with and is driven by the worm 25, see Fig. 1. The worm 25 extends loosely within a suitable recess 11^a in the cylindrical head 11', and is fast on the upper 40 end of a vertically extending shaft 26. The lower end of said shaft 26 extends loosely through a bracket or bearing 27, attached to the loom side. The vertically moving shaft 26 has a square shaped portion 26' 45 thereon, which moves longitudinally in the elongated hub 28' of a bevel pinion 28, see Fig. 5. The hub 28' of the bevel pinion 28 extends out from said pinion on its upper and lower side, as shown in Fig. 5, and the 50 upper part of said hub is loosely mounted in a bearing 29 attached to the loom side, and the lower part of said hub is loosely mounted in a bearing 30 attached to the loom side, see Fig. 5.

55 Upon the vertically extending shaft 26 is secured a circular disk 26^a, which extends between the fork shaped end 31' of a lever 31, and has a hub 31" pivotally mounted on a stud 32 secured to the loom side. There is 60 an extension 31''' on hub 31", to which is connected one end of a helically coiled contraction spring 33; the other end of said spring 33 is connected to an ear 34 on the loom side 1, see Fig. 1; said spring 33 acts 65 to draw down the lever 31. A flexible con-

nexion or chain 35 is attached at one end to the lever 31, and passes over a guide sheave or pulley 35', to the shuttle box motion at the other end of the loom, of usual construction, not shown.

The raising and lowering of the shuttle boxes, raises and lowers the lever 31, through the flexible connection 35, and through the engagement of the forked end 31' of said lever with the disk 26^a on the vertically moving upright shaft 26, raises and lowers said shaft, and also the worm 25 fast thereon, which meshes with the worm gear 22 for rotating the magazine, in order to oscillate or rock the magazine according to the position of the change shuttle boxes. If preferred a separate pattern surface may be used for operating the lever 31.

The bevel pinion 28 meshes with and is driven by the toother portion 36' of the cylindrical bevel gear 36, see Fig. 5. The hub 36" of said cylindrical gear 36 is loosely mounted on a stud 37 on the lower end of an upwardly extending arm 38' of a stand 38. The cylindrical gear 36 has thereon four 90 notches 36', see Fig. 4, in which is adapted to extend a projection 39' on a pawl 39. The hub 39" of said pawl 39 is loosely mounted on a stud 40 on the stand 38. The pawl 39 is adapted to be raised by a rod 41, connected at its lower end to said pawl, and at its upper end connected to the transerrer arm 42, see Fig. 1, when said transerrer arm 42 is operated to transfer a bobbin from the magazine. The pawl 39 has a side extension 39' thereon, which engages with the end of a shield 43, to hold said shield in the position shown in Fig. 4. The hub 43' of the shield 43 is in this instance loosely mounted on the elongated hub 36" of the 100 cylindrical bevel gear 36. Extending downwardly from said hub 43' of the shield 43, is an arm 43'', the end of which has a cylindrical extension 43''' thereon, see Fig. 5, in which is yieldingly held, by the helically coiled compression spring 44, a pin 45. The spring actuated pin 45 extends out from its cylindrical holder to engage the ratchet portion 36^b on the cylindrical bevel gear 36, to move said gear one-fourth of its revolution, 115 when the pawl 39 is raised by the transerrer arm 42.

The rotation of the gear 36 turns the pinion 28 and also the upright shaft 26, and as the worm 25 is in mesh with the worm gear 24 of the magazine, the magazine will be rotated one-eighth of its circumference, to carry a new group of bobbins or filling carriers 9 under the transerrer arm 42, after the transfer of a bobbin.

Pivotally connected to the cylindrical projection 43''' on the arm 43, is one end of a connector or rod 46, see Fig. 1; the other end of said connector 46 is pivotally connected with a bolt 47, which is adjustably 130

secured in an elongated slot 48' in one end of a lever 48, which has its hub 48" pivotally mounted on a pin 49 on a bracket 50 on the loom side. The lever 49 has a pin 51 thereon, on which is mounted a roll 52, which engages with the periphery of a cam 53 fast on the bottom shaft 10.

A helically coiled contraction spring 54 is attached at one end to said lever 49, and at 10 its other end to a pin 55 on the loom side 1, and acts to hold the roll 52 in engagement with said cam 53 after the shield portion is disengaged from the pawl 39, in order to revolve the magazine.

15 It will be understood that the details of construction of my improvements may be varied if desired.

Having thus described my invention, what I claim as new and desire to secure by Letters Patent is:—

1. In a weft replenishing loom, a lay, a rotatable magazine for bobbins, means to oscillate said magazine in unison with the shifting shuttle boxes, and to rotate said 25 magazine, said means consisting of a worm gear attached to the magazine, and a longitudinal and rotatable worm coöperating with said worm gear, and means to operate said worm.

30 2. The combination with a magazine for a shifting shuttle box loom, of means to oscillate and rotate the magazine, said means consisting of a worm and worm gear, combined with means to automatically give to 35 said worm a longitudinal and a rotary motion.

3. In a magazine for weft replenishing looms, a rotatable sleeve or hub having thereon supports for the ends of the bobbins, 40 a worm gear attached to said hub, a worm meshing with said gear, and means under the control of pattern mechanism to impart a longitudinal motion to said worm, combined with devices to impart to said worm 45 a rotary motion.

4. In a weft replenishing loom, a magazine for bobbins, means to oscillate said magazine in unison with the shifting shuttle boxes, and to rotate said magazine when a 50 change of filling takes place, said means consisting of a worm, a worm gear, a ratchet and devices to operate the same.

5. In combination, a magazine for bobbins, a worm gear attached thereto, a worm 55 coöperating with said worm gear, a shaft attached to said worm, a mechanism under the control of pattern surfaces to move said shaft longitudinally, and devices to rotate said shaft.

60 6. In a weft replenishing loom, a bobbin magazine, supports for the ends of the bobbins, a shaft having a longitudinal and a

rotary motion, means under the control of pattern mechanism to move said shaft longitudinally, and means to rotate said shaft, 65 and connections from said shaft to the magazine.

7. In a weft replenishing loom, a bobbin magazine, a shaft, means to move said shaft longitudinally, and means to rotate said 70 shaft, said last named means consisting of a bevel pinion through which the said shaft passes, a bevel gear coöperating with said pinion, and connections from said bevel gear to a moving part of the loom, to give said 75 gear a partial rotation when a change of filling takes place.

8. In a weft replenishing loom, a magazine, a shaft connected therewith, means to give said shaft a longitudinal motion, a 80 bevel pinion, a bevel gear connecting therewith, ratchet teeth on said bevel gear, a spring plunger to coöperate with said ratchet teeth, a rotary cam, and connections between said cam and plunger, whereby the said 85 shaft through the ratchet teeth on the bevel gear, and the bevel pinion is given a rotary motion when a change of filling takes place.

9. In a weft replenishing loom, a filling magazine, a pinion, connections from said 90 pinion to the magazine, a gear coöperating with said pinion, a movable stop to hold said gear in a fixed position, and connections between said movable stop and a transfer mechanism, and said transfer mechanism, 95 combined with means to rotate said gear upon the operation of said transfer mechanism.

10. In a weft replenishing loom, a magazine, a pinion, connections from said pinion 100 to the magazine, a gear coöperating with said pinion, ratchet teeth on said gear, a spring plunger coöperating with said ratchet teeth, a movable stop to retain said gear in a fixed position, and connections from said 105 movable stop to the transfer mechanism, to raise said movable stop out of connection with said gear, and said transfer mechanism, a shield to maintain the movable stop in its raised position, during the movement of 110 the spring plunger from one tooth of the ratchet to another, and means to operate said plunger to rotate the gear and bobbin magazine.

11. In a weft replenishing loom, a magazine for bobbins or filling carriers, a worm gear attached thereto, a worm coöperating with said gear, and means, automatically operated, to impart to said worm a rotary and a longitudinal movement.

EPPA H. RYON.
